UNITED STATES PATENT OFFICE

149,981

DESIGN FOR A VEHICLE TRAILER

Walter T. Stopa, Chicago, Ill., assignor to Duo
Coach Company, Chicago, Ill., a corporation of Illinois

Application June 18, 1947, Serial No. 139,787

Term of patent 3½ years

(Cl. D14—3)

To all whom it may concern:

Be it known that I, Walter T. Stopa, a citizen of the United States and a resident of Chicago, in the county of Cook and State of Illinois, have invented a new, original, and ornamental Design for a Vehicle Trailer, of which the following is a specification, reference being had to the accompanying drawing, forming a part thereof, and in which:

Fig. 1 is a perspective view of a vehicle trailer, showing my new design;

Fig. 2 is a side elevational view of the opposite side of the same;

Fig. 3 is a rear perspective view of the same;

Fig. 4 is a view similar to that shown in Fig. 3, but showing the parts in a different position.

I claim:

The ornamental design for a vehicle trailer, as shown.

WALTER T. STOPA.
